TIE RACK AND METHOD FOR MAKING IT

George Carlson, North Arlington, N. J.

Application January 11, 1947, Serial No. 721,596

3 Claims. (Cl. 211—89)

1

This invention relates to novel racks and more particularly to novel tie racks and to methods for making them. In one of its more specific aspects this invention is directed to highly useful and especially attractive tie racks which are of sturdy construction and yet consist of relatively simple and inexpensive parts. These parts may be produced and assembled in a relatively simple and easy manner and at comparatively low cost.

The various objects and advantages of the present invention will be readily apparent from the following description and drawings, wherein:

Figure 1 is a perspective view of a novel tie rack embodying the invention.

Figure 2 is a foreshortened top plan view of a cut-out blank which is to be worked and ultimately will serve as a locking-spacer element of a tie rack embodying the invention.

Figure 3 is a fragmentary perspective view of the cut-out blank shown in Figure 2 after it has been folded to provide a channel.

Figure 4 is a fragmentary perspective view of the tie-holding means coupled with the locking-spacer to maintain the tie holders in predetermined position with respect to each other.

Figure 5 is a plan view of the tie-holding means employed in the invention.

Figure 6 is an enlarged sectional-perspective view taken on line 6—6 of Figure 4 in the direction of the arrows.

According to this invention the novel tie rack may comprise a plurality of individual tie-holders 10 locked in position with respect to each other by a locking-spacer 11. This unitary assembly may be coupled with a support 12.

As shown in Figure 5, the individual tie-holder 10 resembles the well known cotter-pin and modified so as to have a pair of short feet. The individual tie-holder 10 consists of a length of wire so formed as to provide a loop 15 of appreciable diameter integral with a pair of equi-length elongated legs 16, each of which terminates in a short foot 17 disposed at an angle and preferable at approximately right angles to legs 16. The feet 17 extend outwardly from legs 16 and away from each other. The length of each foot 17 approximates the overall radius of the loop 15.

The locking-spacer 11 may be readily produced by first providing a blank 19 having a plurality of cuts 20, of the same shape and size, spaced equidistant from each other to provide tabs 21 and 22. The tabs 21 are of the same shape and size and the tabs 22 are one-half the size of tabs 21 and are located at the extreme positions. The width of the individual cut-out 20 approximates

or is just slightly greater than the widthwise dimension of legs 16 when combined. The width of each tab 21 approximates or is just slightly greater than the distance between the free ends of feet 17.

The blank 19 is folded over so that the elongated continuous edge thereof is located in the same plane as the lower extremities of the cut-outs 20 to provide channel-way 25 as shown in Figure 3. 10 After the blank 19 has been folded over to provide the channel shown in Figure 3, the tie-holders 10 are inserted therein with the legs 16 thereof located opposite the adjacent cut-out 20 and the feet 17 located in the bottom of the channel-way. 15 Then the sides of the channel-way are pressed so as to be brought close to each other and contiguous and the tabs 21 and 22 are then bent over the continuous straight edge of blank 19 and folded over outer face of that side of blank 19 to lock the tie-holders 10 in position with respect to each other and to the locking-spacer 11. When pressure is applied to the blank 19 to force those portions of the blank 19 to each other, there are deformations of each side of the blank to lock 20 the feet 17 in position to prevent the holders 10 from pulling away from the locking-spacer and also to lock the holders 10 from sidewise movement. By providing this assembly the feet 17 are located in approximately the same straight line and all of the holders 10 are similarly disposed with respect to each other, with the loop portions 15 all being the outer free ends of the holders and being closely adjacent to each other.

This assembly may be readily and frictionally 35 coupled with the support 12 which may consist of a metal, wood, or plastic elongated member having a slot therein in which is located the elongated locking-spacer. The holders 10 extend outwardly from the support 12 and provide a 40 number of spaces 30 for accommodating the ties. This assembly is generally mounted in horizontal position by the use of a pair of screws or other attaching convenient means which may extend through an opening 31 located at each end of support 12.

A tie may be placed on the holder 10 by first folding the tie intermediate its ends and inserting the so formed loop over a loop 15 and between a pair of adjacent loops 15 and the tie will then 50 rest on legs 16 and extend through the spaces 30 between said legs and the adjacent legs 16 on either side thereof.

While this invention has been described in detail, it is not to be limited thereby because 55 it is subject to various changes and modifications without departing from the spirit thereof.

I claim:

1. A tie rack comprising a metallic channel member having sides, a plurality of individual tie-holders, each of said tie-holders terminating in a loop at one end and a pair of oppositely extending feet at the other end, said tie-holders similarly disposed side by side, the feet of said holders located in said channel member, disposed lengthwise along the length of said channel member and being approximately in alignment lengthwise and means for maintaining the sides of said channel near each other.

2. A tie rack comprising an elongated metallic channel having sides, and a plurality of tie-holders, each of said tie-holders comprising a loop, a pair of elongated legs extending from said loop and short oppositely extending feet integral with said legs and disposed at an angle thereto, said tie-holders similarly disposed side by side with the feet of said tie-holders disposed in approximate alignment in the lower part of said channel, those portions of the inner faces of said sides of said channel, located between two pairs of adjacent legs, being close to each other, and a plurality of similar tabs integral with one of said sides lapping over the edge and disposed close to the outer face of the other side.

3. A tie rack comprising an elongated metallic channel having sides, a plurality of substantially equally spaced similar tabs extending from the

elongated edge of one side of said channel, a plurality of tie-holders, each of said tie-holders comprising a loop, a pair of elongated legs integral with said loop and extending therefrom, and a short foot integral with each of said legs at the end thereof remote from said loop, said feet being in approximate alignment and disposed at an angle to said feet, said tie-holders similarly disposed side by side with the feet thereof located in said channel, those portions of the sides of said channel, located between two pairs of adjacent legs being close to each other, said tabs carried by one side, folded over the edge and adjacent to the outer surface of the other side of said channel.
